(57) **CLAIM**

The ornamental design for an oyster adductor muscle cutter, as shown and described.

DESCRIPTION

FIG. 1 is a left rear perspective view of an oyster adductor muscle cutter of the present invention;

FIG. 2 is a top plan view thereof;

FIG. 3 is a rear view thereof;

FIG. 4 is a right side view thereof;

FIG. 5 is a front view thereof; and,

FIG. 6 is a bottom plan view thereof.

The broken lines showing environmental structure is for illustrative purposes only and form no part of the claimed design.
